UNITED STATES PATENT OFFICE.

THOMAS SHAFFER, OF PHœNIXVILLE, PENNSYLVANIA, ASSIGNOR TO THE PHœNIX IRON COMPANY, OF SAME PLACE.

ROLLING-MILL.

SPECIFICATION forming part of Letters Patent No. 276,086, dated April 17, 1883.

Application filed May 19, 1882. (No model.)

To all whom it may concern:

Be it known that I, THOMAS SHAFFER, a citizen of the United States, and a resident of Phœnixville, Chester county, Pennsylvania, have invented certain Improvements in Rolling-Mills, of which the following is a specification.

My invention consists, mainly, in combining with grooved rolls and guides jaws for seizing the bar to be rolled, and mechanism whereby the said jaws are caused to force the bar through the guides, deliver it to the rolls, and release the bar, all substantially as described herein-after, the object of my invention being the more certain and accurate presentation of the bar to the rolls than by the usual plan of directing it to the same by hand, and to prevent the usual losses resulting from imperfectly-rolled bars.

In the accompanying drawings, Figure 1, Sheet 1, is a plan view, partly in section, of rolls with my improvements; Fig. 2, a vertical section on the line 1 2, Fig. 1; Fig. 3, a perspective view of the guide-box and guides; Figs. 4 and 5, the shapes of the bar before and 25 after it passes between the rolls; Figs. 6 and 7, Sheet 2, sectional diagrams illustrating the operation of my invention; and Fig. 8, a perspective view of the delivery-jaws.

A A' are the housings, and B B' the upper and lower rolls, having journals *a*, adapted to bearings in the housings, between which is permanently secured the guide-box D, referred to hereinafter. In front of the rolls is a frame, composed in the present instance of two bars, E E', and the cross-piece F, the frame resting on any suitable foundation, and the rear ends of the bars being preferably secured to the housings. These bars E E' are the supports and guides for the cross-plate G, carrying the jaws h h'. It will be well to explain at this point the action and object of these jaws, reference being had to Figs. 4, 5, 6, and 7. We will suppose that a bar of the oval section shown in Fig. 4 has to be converted into a round bar, Fig. 5, by one pass between the rolls. The oval bar is adjusted between the jaws and its end directed into the flaring entrance to the guide in front of the rolls, when the jaws close on the bar, and, moving in the direction of the arrow, Fig. 6, thrust the end of the bar between the guide-blocks p p to the

rolls, the jaws releasing the bar as soon as it has been seized by the said rolls. The main object of the delivery-jaws is to direct the heated bar to the guides, and thence to the 55 rolls, with greater precision than can be effected by the usual plan of simply pushing the bar by hand through the guides. Thus it is important that the oval bar should be held in the position Fig. 4, and should be prevented 60 from turning as it is delivered to the rolls; otherwise the bar might be imperfect throughout its entire length.

It has been found in practice that there is much less waste in bad bars when the delivery-jaws are used than when the bars are fed 65 by hand in the usual manner, and this is especially the case in making long bars and round bars of large diameters.

Different mechanical devices may be used 70 in connection with the delivery-jaws; but I will proceed to describe the mechanism which I have found to be available in practice, without, however, desiring to restrict myself to that mechanism in carrying my invention into effect. 75

The jaws h h' form parts of the levers H H', which are so shaped and so pivoted at b b to the cross-plate G that when the levers are moved on their pivots in the direction of the arrows, Fig. 1, the jaws will grip the bar, and 80 when moved in the contrary direction will release the same. Chains d d, connected to the levers, pass over pulleys f f on the guide-frame, and from the ends of the chains are suspended weights g g, which tend to draw the jaw-levers 85 and the plate G, to which they are pivoted, away from the rolls. The jaw-levers are also connected by chains i to a windlass-shaft, I, adapted to suitable fixed bearings, m, and provided with a cog-wheel, J, into which gears a pinion, 90 K, on a shaft which has its bearings in a frame or stand, M, and which is provided with a suitable handle, w. When the chain is unwound from the windlass-shaft and the levers H H' are under the influence of the weights g g, the 95 jaws will be open and ready for the reception of the heated bar. As soon as the end of the bar has been adjusted to the flaring entrance of the guides an operative stationed at the handle w turns the windlass-shaft, moves the 100 levers in the direction of the arrow, Fig. 1, and closes the jaws so as to grip the bar, after which

the turning of the windlass-shaft is continued, and both the jaw-levers and plate G are drawn toward the rolls. As soon as the rolls seize the bar and there is a pull on the latter the jaws will open and offer no resistance to the free passage of the remainder of the bar through the rolls. In the meantime the windlass-shaft is so turned that the chains *i i* will be unwound therefrom, thereby permitting the weights *g g* 5 to draw the jaw-levers and plate G away from the rolls until the said plate G is arrested by stops *y* on the guide-bars, when the jaws will be in a condition to receive another bar. The pivots *b b* of the levers *H H'* are adjustable in 10 the plate G, and hence the jaws themselves are adjustable, so that their proper action on the bar may be assured. There is a grooved pulley, *k*, on a shaft, which has its bearings on brackets at the front end of the guide-frame, 15 this pulley being adapted to the bar to be rolled, and thereby facilitating the proper introduction of the said bar between the jaws. 20 The guide-box D, instead of being attached to the housings in the usual manner, is fitted 25 between the housings and bolted thereto, so as to become an integral part of the same, to insure permanence and stability, the guides *p p* fitting into the box, and being there secured by set-screws passing through a slot in the top 30 of the box, and serving to secure the guides after adjustment.

Without claiming, broadly, the combination, with grooved rolls, of jaws for seizing the bar

and presenting it to the said rolls, I claim as my invention—

1. The combination of grooved rolls B B' 35 and guides in front thereof with jaws for seizing the bar, and with mechanism whereby the said jaws are caused to push the bar through the guide to the rolls, all substantially as set forth.

2. The combination, with the rolls and guides, of the jaws *h h'*, the levers *H H'*, of which the jaws form a part, the plate G, to which the said levers are separately pivoted, and mechanism whereby the said levers are operated and traversed to and fro on supporting-bars, all 45 substantially as described.

3. The combination, with the rolls, of the jaw-levers *H H'*, the plate G, to which they 50 are pivoted, the windlass-shaft I, connected to the levers by chains, and mechanism whereby the said plate and levers are moved away from the rolls, all substantially as specified.

4. The combination of the plate G and its 55 jaw-levers with the rolls, guides, and grooved pulley *k*, situated at the rear of the said jaw-levers, substantially as set forth.

In testimony whereof I have signed my name to this specification in the presence of two sub- 60 scribing witnesses.

THOS. SHAFFER.
